UNITED STATES PATENT OFFICE.

JOHN REICHENBACH, OF PITTSBURG, PENNSYLVANIA, ASSIGNOR OF ONE-HALF OF HIS RIGHT TO ANTHONY WISE, OF SAME PLACE.

IMPROVEMENT IN ARTIFICIAL LIMBS.

Specification forming part of Letters Patent No. 128,907, dated July 9, 1872.

SPECIFICATION.

To all whom it may concern:

Be it known that I, JOHN REICHENBACH, of the city of Pittsburg, in the county of Allegheny and State of Pennsylvania, have invented a new and useful Improvement in Artificial Limbs; and I do hereby declare the following to be a full, clear, and exact description thereof, reference being had to the accompanying drawing forming part of this specification, which represents an artificial leg, the upper portion being in section.

My invention is designed to furnish a closely-fitting and somewhat elastic seat for that part of the stump of the wearer's leg or arm which is inserted within the cavity of the artificial limb when in use; and the nature of it consists in the features of construction hereinafter described and claimed.

In order to enable others skilled in the art to make use of my invention I will proceed to describe the manner in which I put it in practice.

The artificial limb A may be made of any desired material and construction. If it is solid, there is a suitable cavity made at the upper end larger in capacity than the stump to be inserted therein. If the artificial limb is hollow, as is usually the case, no alteration is needed, except to make the cavity large enough.

In order to secure a perfect fit I take a piece of soft sheep-skin, and, having it thoroughly wet, I apply it to that part of the stump of the wearer which is to enter the cavity of the artificial limb, and stretch and work it until it fits close to the skin, taking care that it is also perfectly smooth on the exterior surface. I then take another strip of sheep-skin, similarly wet and pliable, and, wrapping it round the first layer, make it also fit closely. After this I apply other layers of wet sheep-skin one after the other until a sufficient thickness is attained to produce a shell which, when dry, will be thick enough to retain its shape. In making this shell it is left open at the bottom, so that there may be no contact with the extremity of the stump. The second layer of sheep-skin which forms this shell is not pasted or glued to the first one, which is next to the wearer's skin, but the third and subsequent layers are pasted or glued so that they will adhere together. When the shell thus formed is dry enough to bear re-

moval from the stump without changing its shape, which will be the case in from ten to fifteen minutes, it is removed and laid aside until it becomes dry, when it will be hard and stiff enough to retain its shape permanently. When dry, the inner or first layer of sheep-skin, which was not glued to the second layer, is easily removed, for the purpose of allowing for shrinkage of the shell. If the sheep-skin shrink so much that the removal of one layer would not be enough to make allowance for this shrinkage, two or more inside layers may be applied without paste or glue, so that they may be removed as described. I then take a plastic material, the composition of which will be herein-after explained, and place it within and around the upper extremity B of the cavity of the artificial limb, as at C in the drawing, and while yet soft and plastic the shell of sheep-skin, formed as hereinbefore described, is inserted, and the limb is properly adjusted as to length and position. The artificial limb is then laid aside until the plastic material becomes hard and dry. It is then ready for use, the plastic material C adhering both to the artificial limb and to the sheep-skin shell, which is the shape of the cavity required to fit the stump, and forming the seat for the stump, while the sheep-skin shell forms the lining. Care should be taken not to close up the cavity at the lower end with the plastic material, but to leave it open, and thus avoid any pressure on the extremity of the wearer's limb.

If the wearer is not present to have the sheep-skin shell fitted to the stump, a pattern may be made of the stump of the leg or arm by means of a plaster cast or otherwise; but, as such cast shrinks and would cause too tight a fit in the seat of the limb, I prefer to make the sheep-skin shell directly from the person of the wearer.

If at any time any alteration is required in the shape of the seat, arising from swelling or shrinkage of the end of the stump, the lining or shell C which forms the seat may be removed from the cavity of the artificial limb and a fresh one inserted in the manner before described.

Various compositions might be used for the plastic material composing the seat of the stump, but I prefer to use a mixture of glue and wood-filings. I take ordinary glue and the filings of wood, (soft wood, such as pine,

being preferable.) The glue is dissolved in water to the consistency ordinarily used by carpenters and then the wood-filings are thoroughly mixed with it, using about half, by measure, of each. Wood-filings are preferable to saw-dust, as being much finer and mixing more intimately with the glue. This makes a very plastic material, which, dry, is somewhat elastic and is very well adapted to the purpose. A seat thus formed has the additional advantage of fitting so closely to the stump as usually to prevent the necessity of employing any fastenings or bandages to secure the limb to the stump when in use.

I am aware that a seat or socket has been formed in an artificial limb by the use of successive layers of pliable material and with padding to provide for inequalities of surface; but I am not aware of a prior use of a plastic, as distinguished from a pliable, material for such purpose, or of a material capable of receiving

and retaining an imprint of the stump or of its pattern without vulcanization.

What I claim as my invention, and desire to secure by Letters Patent, is—

1. An inner socket or seat in the upper end of an artificial limb formed by means of the stump or its pattern being embedded in a suitable plastic material such as will receive and retain, without vulcanization, an exact imprint of such stump or pattern, substantially as described.

2. As a lining for a socket of artificial limbs, a composition of glue and wood-filings or other similar substances, substantially as and for the purposes set forth.

In testimony whereof, I, the said JOHN REICHENBACH, have hereunto set my hand.

JOHN REICHENBACH.
